UNITED STATES PATENT OFFICE.

POWHATAN J. WOOLDRIDGE, OF PEWEE VALLEY, KENTUCKY.

SAFETY APPARATUS FOR ELEVATORS.

Application filed May 10, 1919, Serial No. 296,259. Renewed November 1, 1922. Serial No. 598,437.

To all whom it may concern:

Be it known, that I, POWHATAN J. WOOLDRIDGE, a citizen of the United States, residing in Pewee Valley, Oldham County, Kentucky, ⁵ have invented certain new and useful Improvements in Safety Apparatus for Elevators, fully described and represented in the following specification and the accompanying drawings, forming a part of the same.

10 My invention relates to safety apparatus for elevators, for interrupting the propulsion of the car when a shaft door is opened with the car near the corresponding landing, and in some cases, for preventing the door from opening except when the car is close to the corresponding landing.

A principal object of the invention is to provide stopping means, or, otherwise expressed, propulsion interrupting means, ²⁰ which acts with certainty, and without jarring the car, to discontinue propulsion, or to prevent the starting of the car after propulsion has been discontinued, when the door is opened with the car near the corresponding landing, and which will be effective when the car has come to a complete stop or is still oscillating within reasonable limits near the landing at the moment the door is opened. Another object is to provide simplified and ³⁰ improved means, cooperating with the stopping means, to prevent the door from being opened unless the elevator is near the corresponding landing. Another object is to improve and simplify in certain respects the invention set forth in my application, Serial ³⁵ No. 265,194, filed December 4, 1918, for Safety apparatus for elevators.

The objects, characteristics and advantages of my invention will be further explained so far as is necessary in connection with the following detailed description of an exemplifying structure embodying the invention. After considering this, it will be understood that the invention may be embodied ⁴⁰ in other forms, and I do not limit myself to details except as claimed. In the drawings:

Fig. 1 is a front elevation of an elevator car carrying part of the mechanism embodying the invention;

Fig. 2 is an enlarged elevation of the mechanism carried by the car;

Fig. 3 is an elevation of part of a shaft

door and door casing looking toward the shaft, showing in section the part of the mechanism located in the shaft and on the ⁵⁵ door; and

Fig. 4 is a horizontal section of the same showing also a portion of the car and the car mechanism.

The car C is arranged for electrical propulsion, and has the usual controller box B. Leading from the box is a conductor K, forming a part of the control circuit, or else constituting a special safety circuit, so arranged that when it is broken, the control circuit of the car will be broken, to interrupt propulsion of the car, and, if desired, the ⁶⁰ brake will also be applied.

At a convenient place on the car, in this instance on the top near one corner, is a circuit-breaking mechanism supported by a frame 10. At the top and bottom, this frame has sockets or guides 11 in which rods 12, 13, are mounted to reciprocate, the rods being in this case of rectangular form. Rod 12 has a part 14 bent at a right angle, and rod 13 has a similar part 15. Between the members 14 and 15 are arranged a series of circuit-breaker-operating plates, or strips, 16 which have their operative ends bevelled at top and bottom at 17 forming on each plate a point 18. The series of plates thus has a serrated operative edge. Vertical guide rods 20, 21, are secured to member 15 and extend up through ⁷⁰ slidably fitting holes in plates 16 and in upper member 14. Rod 20 is provided at its top with a contact 22 insulated from the rod at 23. Member 14 carries a bracket 25, insulated at 26, and the bracket is provided with a contact 27 to cooperate with contact 22 to ⁷⁵ open and close the safety, or stopping, circuit, K.

The circuit breaker plates 16 with their top and bottom plates 14 and 15 and their guide rods, are normally held together and ⁸⁰ properly located in the stationary frame 10 by the following means: A rod 30 is connected to bottom plate 15 and passes through a guide sleeve 31 carried by frame 10, and also passes through a hole in frame member ⁸⁵ 32. The rod is provided with a stop 33 arranged to strike the bottom of sleeve 31 and limit upward movement of the breaker elements. This stop also serves as an abutment ⁹⁰ 100

for spring 34, which surrounds the rod and is compressed between the stop 33 and frame member 32. Another guide rod 35 is connected to top plate 14 and passes through a 5 guide sleeve 36 carried by frame 10 and also through frame member 37, and is provided with a stop 38 to engage the top of sleeve 36 and limit downward movement of the breaker group, and with a spring 39 compressed 10 between stop 38 and frame member 37. In some cases, the rods 30 and 35 may be provided with nuts 40 arranged below and above the frame members 32 and 37, respectively, and in this case, the nuts will serve to limit 15 movement of the breaker group, and the stops 38 may then be adjusted to different positions on the rods to vary the spring action.

If any device of moderate thickness is 20 passed between any two of the plates 16, they are forced apart, and top plate 14 is moved away from bottom plate 15, and the controlling circuit is broken at the contacts 22, 27.

25 This stopping action is performed by an operating arm 45 movably supported at a suitable place in the shaft near a door D. In the present instance, the arm 45 is located in the shaft door casing above the top of the 30 door. The arm is supported by a guide plate 46 secured to the door casing, as by screws 47. In the plate is a guide slot 48 having a part 49 parallel to the door, and another part 50 at a right angle to the first. 35 The breaker operating arm is connected by bolts 51 with a plate 52 which lies below guide plate 46 while arm 45 lies above it. On the bolts are mounted rollers 53, 53^a, which travel in the guide slot 48. Arm 45 40 has at the end near the rollers a lug 54, arranged to be engaged by roller 55 mounted on a stud 56, which is carried by a plate 57 secured to the top of the door. Lug 54 is shaped to partially surround roller 55 when 45 the door is closed, and terminates in an end member 54^a. A spring 58 is connected at one end to a fixed point, such as a screw stud 59, which is screwed into a plate 60 in the well, and at the other end to an eye 61 on 50 arm 45 near roller 53. The operative part of arm 45 is, as best shown in Fig. 2, in the shape of a thin wedge or blade with its edge directed toward the ends of breaker plates 16.

55 When the car is close to a landing and coming to rest after power has been cut off, it may drift slowly for a short distance before it stops completely, and in some cases, especially where the car is supported by long cables or a long hydraulic column, it may 60 oscillate several times up and down before it comes completely to rest. Regardless of whether the car is completely stopped or is moving moderately, so long as it is substantially opposite the landing or within a distance measurable by the vertical extent of

the breaker plates 16 in the present case, when the door is opened, roller 55 in contact with lug 54 moves arm 45 first straight to the left a short distance against the pull of spring 58 until roller 53 reaches the bevelled face 49^a of the guide slot, and thereupon the combined effect of the push of the roller and the pull of spring 58 is to move roller 53 down to the end of branch 50 of the slot, 70 while roller 53^a travels to the end of branch 49 of the slot. That is to say, after a slight linear movement to the left, the arm pivots about a shifting point somewhere between rollers 53 and 53^a, and swings out into contact with the points of breaker plates 16, 75 and engages between two of the points, and then by acting on the bevelled faces 17 of the adjacent plates, forces the plates apart, and finally the arm assumes approximately the position in which it is shown in Fig. 2. 80 As arm 45 nears its final outward position, shown in dotted lines in Fig. 4, roller 55 cooperates with end member 54^a of lug 54 to positively complete the outward movement 85 of the arm, and thereafter the roller is released, so that opening movement of the door can be completed, as fully explained by the dotted lines. Spring 58 then retains the arm in active position until the door is 90 closed.

95 As soon as any two of the plates are slightly separated, and thereafter until the arm is withdrawn, the safety circuit K is broken at the contacts 22, 27, and the driving circuit is interrupted if it was closed at that moment, or if it was not closed, it is prevented from being closed to drive the car in either direction, and the car comes to rest as soon as its slight drift or oscillation above referred to ceases. The movement of the car 100 within reasonable limits after arm 45 engages between any two of the breaker plates is permitted by the movement of the breaker group, comprising plates 16, top and bottom plates 14, 15, rods 12, 13, 30 and 35 in 105 relation to the frame 10 fixed on the car. Springs 34 and 39 yield sufficiently to permit this movement, and after arm 45 is withdrawn, if the breaker group was held away 110 from the central position in relation to the frame 10, by the arm, these springs return the breaker group to normal position. 115

120 The arm is withdrawn by the closing movement of the door, which first causes roller 55 to strike the arm and swing it so that first roller 53^a moves to the right along part 49 of the guide slot, and then roller 53 moves up through part 50 of the slot and then along bevelled face 49^a, and finally spring 58 assists in pulling the arm back to 125 its normal position, as shown in Fig. 4, and by the action of lug 54 on roller 55 assists in the final closing of the door.

130 Bevelled faces 17 of the breaker plates have a cam-like action on the edge of arm

45 as the arm is withdrawn, which assists in moving the arm quickly away from its final engagement with the plates.

The safety, or stopping, circuit K is therefore reestablished at the contacts 22 and 27, and the car may be operated as usual.

It is desirable in some cases to provide means for preventing opening the door unless the car is close to the landing. This is provided for in a simple way in the present invention. A door latch member 70 is pivotally mounted on a stud 71 screwed into plate 60. This latch member has an arm or finger 72 normally lying close to the edge of the door casing and confronted by a vertical rail 73 on the car, the length of the operative part of this rail usually being the same as the effective length of the breaker group. Near the other end of the latch member it is provided with a latch 74 arranged to cooperate with a tooth 75 formed on the upper end of stud 56. The latch member also has near the latch a face 76 arranged to engage the back of stud 56 when the door is closed. The latch member is acted upon by a spring 77 coiled about stud 71 and having one end engaged with the latch member, and the other end engaged with stud 59 so as to urge the latch member to rotate counterclockwise in Fig. 4. If it is attempted to open the door when the elevator is nearly opposite the landing, rail 73 is opposite arm 72 of the latch member, and when the tooth 75 of stud 56 moves to the left, contact of arm 72 with the rail 73 prevents hook 74 moving inward sufficiently to engage the door, and the door may be opened freely. But if the car is not in proper position, the absence of rail 73 permits the arm 72 to swing outward when the back of the stud 56 moves away from part 76 of the latch member to bring latch 74 into engagement with tooth 75 and prevent further movement of the door. On return of the door to fully closed position, the latch member 70 is caused to swing back to normal position entirely away from possible contact with any part of the car by reengagement of the back of stud 56 with part 76 of the latch member.

An important feature of the invention is that all the parts of the safety mechanism which are located in the shaft, are outside of the path of movement of the car and of any parts carried by the car, and are in fact outside the inner limits of the shaft, except when it is attempted to open a door. Unnecessary contact between parts of the safety mechanism located on the car and in the shaft is thus avoided, and the chance of breakage reduced to a minimum.

What is claimed is:

1. The combination with an elevator shaft, a shaft door, a car, and electrical car controlling means including a circuit, the in-

terruption of which is effective to stop the car, of a breaker for said circuit, and means actuated by the door when the car is near the corresponding landing to positively engage and actuate the breaker regardless of slight movement of the car adjacent to the landing and to remain in positive engagement with the breaker and to maintain said circuit open until the door is closed.

2. The combination with an elevator shaft, a shaft door, a car, and electrical car controlling means including a circuit, the interruption of which is effective to stop the car, of a breaker for said circuit, and means actuated by the door when the car is near the corresponding landing to positively engage and actuate the breaker regardless of slight movement of the car adjacent to the landing and to remain in positive engagement with said breaker and to maintain said circuit open until the door is closed, said means when inactive being entirely outside the path of car movement in the shaft.

3. The combination with an elevator shaft, a shaft door, a car, car propelling means, and means for controlling the propelling means, of automatic stopping means acting upon the controlling means, comprising two or more separable members carried by the car, and an extensible member located on the shaft and actuated by opening of the door to enter between two of said separable members and push them apart and thereby interrupt propulsion of the car until the door is closed.

4. The combination with an elevator shaft, a shaft door, a car, car propelling means, and means for controlling the propelling means, of automatic stopping means acting upon the controlling means, comprising two or more separable members carried by the car, an extensible member located on the shaft and actuated by opening of the door to separate two of said separable members and interrupt propulsion of the car until the door is closed, and means supporting said separable members movably in relation to the car to permit moderate movement of the car while said extensible member is in engagement with the separable members.

5. The combination with an elevator shaft, a shaft door, a car, car propelling means, and means for controlling the propelling means, of automatic stopping means acting upon the controlling means, comprising a fixed frame on the car, a group of vertically arranged separable members flexibly supported in the fixed frame, the outward ends of said members being mutually shaped to provide notches communicating with the meeting surfaces of the members, an operating member located on the shaft, a guide supporting said member for an initial longitudinal and subsequent swinging move-

ment to bring it into engagement with said separable members, a spring resisting movement of said member, and a member carried by the door to move said operating member to active and inactive positions.

6. The combination with an elevator shaft, a shaft door, a car, and electrical controlling means, comprising a safety circuit, of a separable contact in said safety circuit, 10 a plurality of separable, pointed members arranged to open said contact, means for closing said contact, a swinging arm supported in the shaft, and means actuated by movement of the door for moving said arm 15 into engagement with said separable members to open said contact.

7. The combination with an elevator shaft, a shaft door, a car, and electrical controlling means comprising a safety circuit, 20 of a separable contact in said safety circuit, a plurality of separable, pointed members arranged to open said contact, means for closing said contact, a swinging arm supported in the shaft, means actuated by movement of the door for moving said arm into engagement with said separable members to open said contact, and means for supporting said separable members movably in relation to the car to permit moderate movement of 25 the car while said arm is in engagement with the separable members.

8. The combination with an elevator shaft, a shaft door, a car, electric controlling mechanism including a safety circuit, 30 and circuit-breaking mechanism carried by the car, of operating mechanism located in the shaft comprising a guide plate having a guide slot comprising portions arranged at an angle to each other, a swinging arm 35 having studs located in said slot, a part arranged to cooperate with the breaker mechanism and a lug, a member carried by the door and arranged to cooperate with said arm and lug to move the arm to operative 40 and inoperative position, and a spring urging the arm to inoperative position.

9. In elevator mechanism, the combination with safety means acting upon opening the door to interrupt propulsion of the 45 car, of a door latch normally active to engage a member carried by the door to prevent opening the same, and an abutment carried by the car of substantial vertical length acting when the car is nearly oppo-

site the corresponding landing to render the 55 latch inactive.

10. In elevator mechanism, the combination with a shaft, a shaft door, and car, of a safety door-locking member pivoted in a portion of the shaft near the door, a latch 60 on said member, a latch-engaging device on the door, an arm on said member normally lying outside the inner limits of the shaft and arranged to project within the shaft when the door is moved slightly away from 65 fully closed position, a spring urging said member to move on its pivot to cause engagement of said latch with the latch-engaging device and to project said arm into the shaft, means on the door for restraining 70 such movement when the door is fully closed and for holding said member so that it is entirely outside the inner limits of the shaft, and an abutment carried by the car of substantial vertical length arranged to cooperate 75 with said arm when the car is near the landing and the door is opened to prevent locking engagement of said latch with said latch-engaging device.

11. The combination with an elevator shaft, a shaft door, a car, and electrical controlling means, comprising a safety circuit, of a separable contact in said safety circuit, a plurality of separable, pointed members arranged to open said contact, means for closing said contact, a horizontally swinging arm supported in the shaft, and means actuated by movement of the door for moving said arm into engagement with said separable members to open said contact.

12. The combination with an elevator shaft, a shaft door, and a car, of a safety device located on the car and operable to interrupt propulsion of the car, a horizontally swinging operating member mounted 95 on the shaft adjacent said door, and means whereby the opening of said door said member is caused to swing in a horizontal plane into engagement with said safety device to bring the same into operation.

In testimony whereof I have hereunto set my hand in the presence of two subscribing witnesses.

POWHATAN J. WOOLDRIDGE.
